UNITED STATES PATENT OFFICE.

BENJAMIN W. NEWLOVE, OF SOUTH CHARLESTON, OHIO.

COFFIN-LOWERING ATTACHMENT.

SPECIFICATION forming part of Letters Patent No. 360,239, dated March 29, 1887.

Application filed July 21, 1886. Serial No. 208,598. (No model.)

To all whom it may concern:

Be it known that I, BENJAMIN W. NEWLOVE, a citizen of the United States, residing at South Charleston, in the county of Clark, 5 State of Ohio, have invented certain new and useful Improvements in Coffin-Lowering Attachments, of which the following is a specification, reference being had therein to the accompanying drawings.

10 My invention relates to improvements in devices or attachments to coffins or caskets by which they are lowered into the grave.

The object of my invention is to provide a simple and efficient device by which the lowering-straps are readily attached to and detached from the coffin or casket.

Figure 1 is a view in perspective of a coffin or casket with the lowering-straps secured to each corner. Fig. 2 is a view in perspective 20 of the strap attachment and eye in a detached position. Fig. 3 is a side view of the strap attachment and sectional view of the eye detached. Fig. 4 is a view in perspective of the strap attachment and eye joined together as 25 in use. Fig. 5 is a sectional view of the pendant and strap with the devices for attaching the strap to the pendant.

A indicates the coffin or casket, to the four corners of which are secured the eyes B. The 30 eyes or staples B are provided at their rear ends with a screw-threaded shank, C, or other suitable fastening device, by which they are secured to the side of the coffin or casket, the front ends of said eyes being provided with an open-ended recess, D, which is contracted 35 at its front end, for a purpose to be described hereinafter.

The upper side of the eye B is provided with an inclined or convex surface, E, which 40 permits the strap attachment to slide off when the straps are turned around and loosened, and thus become detached from the eye.

The under side of the eye B is provided with a concave recess, F, adapted to receive 45 the ball on the lower end of the pendant or strap attachment, and by which means the ball attached thereto is prevented from slipping out of the eye, as shown in Fig. 4.

G is the pendant or device which is at-

tached to the end of the lowering-straps H, the 50 shank I of said pendant being provided with suitable apertures to receive the rivets by which the pendant is secured to the strap, said rivets being passed through the sleeve H'.

The pendant G is provided with an inclined flanged portion, K, below which is formed the flat portion L, adapted to enter the contracted or narrow portion D of the eye B.

M is a round portion of the pendant, located below the flat portion L, on the lower end of which is formed the ball N, adapted to enter the concaved recess F of the eye.

In placing the pendant of the lifting-strap in the eye the thin or narrow portion L is inserted into the contracted portion D of the eye. The pendant is then raised and turned to the position shown in Fig. 2 until the ball N enters the concave recess F, when the pendant will be securely attached to the eye, 65 so that it will not become detached until the pendant is turned again into the position in which it was inserted.

When it is desired to release the pendant from the eye after the casket has been lowered into position, straps and pendants are turned and the straps are slackened, when the pendant will drop until the inclined portion K strikes the inclined face E of the eye, which allows the pendant to slide out of the eye, and 75 thus disengage itself. These devices just described, being small and strong, do not take up much room, and afford a ready and convenient device for operation, while at the same time the eyes, when made of a bright 80 metal or silver-mounted, give an ornamental appearance to the coffin or casket.

The lower portion of the straps are, by preference, made round, so that they can be 85 readily turned to lock or unlock them from the eyes, or they may be made round throughout their entire length.

Having thus described my invention, what I claim, and desire to secure by Letters Patent, is—

1. A lowering device for attachment to coffins or caskets, consisting of the open eye B, having a contracted opening, D, and concave

recess F, in combination with the strap H and the pendant G, having the flat portion L and ball N, as set forth.

2. A lowering device for attachment to cof-
5 fins, consisting of the open eye B, having its upper portion beveled or convex, in combination with the pendant G, to which the lowering-straps are attached, said pendant being provided with the inclined flange K, whereby

the pendant is disengaged from the eye by the slackening of the strap, as set forth.

In testimony whereof I affix my signature in presence of two witnesses.

BENJAMIN W. NEWLOVE.
